UNITED STATES PATENT OFFICE

168,340

ELECTRIC HEATER

Francis Gallay, Collonge-Bellerive, Switzerland,
assignor to Intertherm A. G. Fabrik fur elek-
trische Apparate (Intertherm S. A. Fabrique
d'appareils électriques), Zurich, Switzerland, a
corporation of Switzerland

Application June 13, 1952, Serial No. 20,182
In Switzerland February 7, 1952

Term of patent 14 years

(Cl. D81—10)

To all whom it may concern:

Be it known that I, Francis Gallay, a citizen of Switzerland, residing at Collonge - Bellerive (Geneva), Switzerland, have invented a new, original, and ornamental Design for an Electric Heater, of which the following is a specification, reference being had to the accompanying drawing, forming a part hereof.

The figure is a perspective view of an electric heater embodying my new design. The rear side of the electric heater is substantially like the front side thereof shown in the drawing.

I claim:

The ornamental design for an electric heater, as shown and described.

FRANCIS GALLAY.
